Inventor:

UNITED STATES PATENT OFFICE.

ALBERT C. FISCHER, OF CHICAGO, ILLINOIS.

EXPANSION-JOINT-INSTALLING DEVICE.

Application filed October 19, 1925. Serial No. 63,364.

To all whom it may concern:

Be it known that I, ALBERT C. FISCHER, a citizen of the United States, residing at Chicago, in the county of Cook and State of Illinois, have invented a new and useful Improvement in Expansion-Joint-Installing Devices, of which the following is a specification.

This invention relates to a combination of a strip of expansion joint and a false strip which completes the sides of the joint but which may be removed after the pouring of the concrete and a filler poured therein.

The invention consists of a base portion consisting of the expansion joint, and a crowning portion consisting of preferably a wood strip having nails suitably placed therein so that the strip can be anchored 20 on the expansion joint and easily removed therefrom. The strip need not necessarily be fabricated from wood, but may be of any suitable material and may be a suitable plastic material made in strip form having anchoring means, so that the same can be inserted with the expansion joint. The crowning strip may thus be arranged to be temporary in which case the strip would be removed and another suitable filler substituted or the strip may remain permanently.

My invention relates to the combination of a removable crowning strip and an expansion joint base for the purposes later described.

Referring to Figure 1, (b) represents the crowning material, while (c) represents the fastening nails or prongs embedded therein, adapted to be embedded in the top edge of an expansion joint.

Figure 2 illustrates the expansion joint (a) having a crowning strip (b) in place, held in position by the anchoring prongs (c).

Figure 3 illustrates the expansion joint (c) in position with the crowning strip (b), 45 fastened in place by the prongs (c) having poured on either side concrete (d). The crowning strip (b) in this instance can readily be removed, and in Figure 4 all that is left in place after the removal of the 50 crowning strip (b) is the expansion joint base (c) held in place by the concrete walls (d).

The open space previously occupied by (b) in Figure 5 is shown to be occupied by 55 a filling composition (e) which may be either poured, laid, or fastened on the base strip (c) between the concrete walls (d).

My invention relates particularly to mastic expansion material, and does not contemplate the use of metal.

I claim:

1. A joint crown installing device, comprising a strip providing a temporary crown for the expansion joint, said strip having impaling means on its underside adapted to be embedded in the material of the joint for detachably securing the strip to the joint.

2. A joint crown installing device, comprising a wooden strip having a transverse dimension equal to that of an expansion joint, and having impaling prongs driven through the thickness of the same and projecting from its under side, said prongs being adapted to be embedded in the material 70 of the joint for detachably securing the strip to the joint and maintaining an alignment of the strip and joint to completely fill up the space to be equipped with the joint.

In testimony whereof I have signed my 80 name to this specification, on this 8th day of October, A. D., 1925.

ALBERT C. FISCHER.
